POWER OPERATED HAMMERS

Reginald P. Fitzgerald, Braintree, Mass., assignor to Pneumatic Drop Hammer Company, Braintree, Mass., a corporation of Massachusetts

Filed Jan. 31, 1957, Ser. No. 637,427

10 Claims. (Cl. 78—25)

This invention relates to power operated hammers and it is herein disclosed as embodied in a drop hammer wherein an upper die is carried by a ram which, under treadle control, drops of its own weight to bring the upper die into operative engagement with a work piece supported on a lower die. The dies are readily removable and replaceable and the form to which the work piece is shaped depends upon the selection of appropriate dies. The ram, upon release of the treadle, is returned to its upper position by fluid pressure.

Although the various features of the invention are herein disclosed as embodied in a drop hammer of the type above outlined, they are not limited to such use but can be applied to power hammers generally.

It is an object of the invention to provide a power hammer in which the ram is not only cylindrical and long with respect to its width but also is massive with respect to the cylinder within which it moves and has improved means for guiding the ram so as to give maximum support to the ram at the instant of impact, thereby to prevent deflection of the ram and the attached die and improve the accuracy of the forged article. The invention also includes improved adjustments and improved means for cushioning the shock after impact upon the work piece.

In accordance with this object, a feature of the illustrated machine consists in the provision of a ram carrying upper frame which includes a pair of heightwise extending strong, rigidly supported parallel guide rods slidably engaged by a strong rigid cross piece on the lower end of the massive ram to support the ram against any tendency to deflect at the instant of heavy impact of the upper die against a work piece supported on the lower die. Other features reside in means for adjusting the lower die angularly with respect to the upper die, and in means for adjusting the entire upper ram supporting frame and upper die transversely with respect to the lower die, and also in a plurality of fluid pressure shock absorbing devices for supporting a base which carries the operating instrumentalities of the hammer.

These and other objects and features of the invention will become apparent upon a reading of the following description of an illustrative power hammer, with reference to the accompanying drawings, and will be pointed out in the claims.

In the drawings:

Fig. 1 is a front elevation of an illustrative power hammer embodying the invention;

Fig. 2 is a side elevation viewed from the right of the hammer shown in Fig. 1;

Fig. 3 is a vertical section taken on the line 3—3 of Fig. 2;

Fig. 4 is a large scale vertical section taken on the line 4—4 of Fig. 1;

Fig. 5 is a horizontal section taken on the line 5—5 of Figs. 1 and 2;

Fig. 6 is a horizontal section taken on the line 6—6 of Fig. 1;

Fig. 7 is a vertical section taken on the line 7—7 of Fig. 6 showing one of the shock absorbing supports before the pressure fluid is turned on;

2

Fig. 8 is a view similar to Fig. 7 but showing the support in normal operative position with the pressure fluid turned on;

Fig. 9 is a view similar to the upper portion of Fig. 3 but to a larger scale;

Fig. 10 is a view similar to an intermediate portion of Fig. 2 but to a larger scale;

Fig. 11 is a plan view of the power hammer to a large scale and with a part broken away.

10 Fig. 12 is a horizontal section of the main valve system showing the positions of the valves before the pressure fluid is turned on;

Fig. 13 is a view similar to Fig. 12 but showing the positions of the valves after the pressure fluid has been turned on;

Fig. 14 is a view similar to Fig. 13 but showing the positions of the valves after the treadle has been depressed; and

20 Fig. 15 is a view similar to Fig. 14 but showing the positions of the valves after the treadle has been allowed to rise.

The work engaging instrumentalities of the illustrated hammer consist of a lower die 20 (Figs. 1 and 3) and an upper die 22. A work piece, not shown, is placed upon the lower die 20 and then, through operator controlled mechanism, the upper die is caused to deliver a heavy blow to the work piece and thereby shape the work piece to a desired form determined by the dies selected. The downward or operative stroke of the upper die is preferably effected by gravity and the upward or return stroke by pneumatic pressure.

The lower die 20 has a depending dovetail 24 (see also Fig. 5) engaging a slot formed in an anvil 26. This slot extends in a direction to provide for forward and rearward adjustment of the lower die. The dovetail 24 is held in adjusted position by a gib 28. The anvil 26 is supported for rotary adjustment in a base 30 (see also Fig. 6). To this end the intermediate portion of the anvil is in the form of a collar 32 and the lower portion of the anvil is in the form of a stem 34 depending from the collar. The collar 32 and the stem 34 are journaled for rotary adjustment in the base 30. An annular horizontal surface on the under side of the collar 32 rests upon a corresponding surface on the base 30 to provide heightwise support for the anvil 26.

45 Rotary adjustment of the anvil 26 is effected by a pair of adjusting screws 36 (Figs. 1, 3 and 5) on opposite sides of the vertical axis of the anvil and threaded through the base 30. The ends of the screws 36 engage flats 38 formed by recesses in the collar 32, either screw being loosened and the other tightened to obtain the desired adjustment.

The base 30 does not rest directly upon the floor or other supporting surfaces but upon four shock absorbers 55 each having a piston 40 (Figs. 7 and 8) from which extends upwardly a piston rod 42 having its upper end in supporting engagement with the base 30. Each piston 40 is movable up and down in a cylinder 44 (see also Fig. 6) having a constantly open orifice 46 below the piston for the admission of air under pressure. The space between each piston and its cylinder wall is sealed by a leather packing cup 48 held against the under face of the piston by a clamping disc 50 and screw 52. The two rear cylinders 44 have their orifices 46 directly connected to air supply conduits 54 and they also have orifices 56, similar to the orifices 46, by which the air pressure is communicated through conduits 58 to the orifices 46 of the two forward cylinders. The conduits 58 are thus, in effect, extensions of the conduits 54.

A T coupling 60 connects the conduits 54 to each other and to a conduit 62 communicating, through an adjustable reducing valve 64, with a conduit 66 con-

nected to any suitable source of air under a suitable pressure above that required. All four cylinders are thus in direct communication with each other and are under equal pressure. The adjustable reducing valve 64 acts to provide the desired pressure which should be sufficient to overcome the weight of the base 30 and all parts of the power hammer supported thereby, and thus normally to maintain all the pistons in their uppermost positions as shown in Fig. 8. Rubber buffers 68 are provided to keep the pistons 49 from hitting the heads of the cylinders 44.

When the upper die 22 strikes a work piece on the lower die 20, the impact transmitted through the anvil 26 and the base 30 will cause the pistons 49 to compress the air in the cylinders and thus cushion the shock transmitted to the floor. A ball type check valve 70 between the stem of the T coupling 60 and the conduit 62 prevents a sudden escape of air from the cylinders 44 back into the conduit 62 when impact further compresses it. The position of the pistons in the cylinders when the hammer is idle and before the air pressure is turned on is shown in Fig. 7.

The upper die 22 has an upstanding dovetail 72 (Figs. 1 and 3) engaging a slot formed in the lower end of a massive cylindrical plunger or ram 74. The ram serves a dual purpose in that it also acts as a piston rod to carry the piston by which the ram is elevated under pneumatic pressure. The slot in the bottom of the ram extends in a direction to provide for forward and rearward adjustment of the upper die. The dovetail 72 is held in adjusted position by a gib 76. The ram 74 is movable heightwise in a strong bearing 140 formed in a top cross member 78 of an upper frame which comprises also a bottom cross member 80 rigidly joined to the top cross member by a pair of uprights 82. The center portion of cross member 80 is broken away in Fig. 1 to show to anvil 26. See also Figs. 4 and 6.

The entire upper frame 78, 80 and 82, together with the cylindrical ram 74 and the upper die 22 (Figs. 1, 3, 4 and 5), is adjustable transversely as a unit with respect to the base 30. To this end a tongue 84 (Figs. 2, 3 and 4) depending from the bottom cross member 80 is guided by a complementary transversely extending groove formed in the upper surface of the base 30. This tongue and groove arrangement permits transverse relative movement only and prevents any turning of the upper frame relatively to the base 30. A pair of coaxial oppositely directed and transversely extending adjusting screws 86 (Figs. 3, 4 and 5) have their ends engaging shallow recesses in upright walls of the bottom cross member 80. These adjusting screws 86 are threaded through upright posts 88 having lower portions which extend down into sockets formed in the base 30, the posts being firmly anchored to the base by coaxial clamping screws 90 threaded in the posts.

These clamping screws 90 are held down by heads 91 countersunk into the base 30.

The desired transverse adjustment of the upper die 22 is effected by loosening one of the screws 86 and tightening the other. Undesired turning of the adjusting screws 86 is prevented by set screws 92 threaded down into the upper ends of the posts 88 and prevented from damaging the threads of the adjusting screws by bronze plugs 94. Clearance spaces 96 (Figs. 3 and 5), formed in the bottom cross member 80, enable the latter to avoid interference with the posts 88 upon transverse adjustment of the upper frame; and a clearance space 98 (Figs. 3 and 5), formed in the bottom cross member 80, enables it to avoid interference with the anvil 26 as the upper frame may be moved transversely of the base in making any necessary lateral adjustment to align the dies.

The transversely adjustable upper frame, 78, 80, 82, is held down on the base 30 by four compression springs 100 (Figs. 1, 2, 4 and 5). Each of the springs 100 surrounds the upper portion of a post 102 and has its upper

end bearing against a washer 104 backed by a nut 106 threaded on the post. The lower end of each spring 100 bears against a washer 108 which rests upon a horizontal surface of the bottom cross member 80. The lower portion of each post 102 is firmly anchored in a short horizontally disposed rod 110 which is free to turn in a somewhat oversized hole 112 formed in the base 30. A flat 114 formed on the rod 110 facilitates construction. The nuts 106 are tightened or loosened to effect a desired compression of the springs 100. The posts 102, while holding the upper frame 78, 80, 82 shown on the base 30, are free to rock transversely in the transverse slots 103, 105 (Figs. 1, 4 and 5) to accommodate transverse movements of adjustment of the upper frame.

As has already been mentioned, the ram 74 is guided for up and down movement in a bearing 140 in the top cross member 78. In addition to this bearing, however, supplemental guides are provided in the form of a pair of upright rigid and sizable rods 116 (Figs. 1 and 3) immovably secured at their upper ends in the top cross member 78 and at their lower ends in the bottom cross member 80. At the lower end of the ram 74 are rigid and preferably integral transverse extensions 118 in which are formed bearings having bushings 120 of considerable vertical dimensions (Fig. 3) for sliding and ram supporting engagement with the guide rods 116. The two extensions 118 together with the end portion of the ram 74 constitute, in effect a strong rigid cross piece on the lower end of the ram. The guide rods 116, being very rigid and acting in conjunction with the two bearings 120 and the upper bearing 140, serve to overcome any tendency of the ram 74 and the related die 22 to deflect or otherwise suffer a turning motion when the upper die 22 strikes a work piece on the lower die 20 under conditions in which the work piece is not in line with the axis of the ram. Furthermore, the transverse extensions 118 serve to augment the weight of the ram 74 and thus increase the impact of the blow delivered by the upper die 22 upon the work piece.

From the foregoing it will be seen that I have provided a rigid upper frame including an upper bearing for the ram proper and two laterally spaced bearings for the lower end of the ram, the lower bearings being supported by the vertical parallel guide rods. This three point support for the ram provides extraordinary rigidity in holding the ram against any deflection under conditions of off center impact. Impact occurs when the extensions 118 are most remote from bearing 140, thus giving bearing spacing which provides the best possible result. The massive cylindrical ram, longer than its diameter, provides for concentration of the mass of ram directly above the point of impact.

The upward stroke of the ram 74 is effected by pneumatic pressure acting upon a piston 122 (Figs. 3 and 9) seated upon a shoulder 124 formed on the upper portion of the ram by a reduction in diameter. A leather packing cup 126 is clamped against the upper face of the piston 122 by a two part clamping disc 128. A two part clamping collar 130, having its split at right angles to the split of the clamping disc 128, has its under face engaging the upper face of the clamping disc. The two halves of the clamping collar 130 are drawn together by screws 132. The engaging faces of the clamping disc 128 and the clamping collar 130 are complementally inclined to effect a downward thrust of the clamping disc when the screws of the clamping collar are tightened. An overhanging shoulder 134, resulting from an increase in diameter of the ram 74, engages the upper surface of the clamping collar 130 to hold the latter against upward movement when clamping pressure is applied. A packing ring 136 on the shoulder 124 prevents air leakage through the piston assembly.

The piston 122 operates within a main cylinder 138 secured at its lower portion in a socket formed in the top cross member 78. The space between the ram 74 and

the bottom of said socket is closed by a bronze bearing bushing 140 surmounted by an annular U-shaped leather packing 142. An air duct 144 (Figs. 9 and 11) in the top cross member 78 opens into the cylinder 138 just above the packing 142. Secured upon the upper end of the cylinder 138 is a cylinder head 146 having vent holes 148 through which the space within the cylinder above the piston 122 is always open to the atmosphere. A valve system for controlling the admission and exhaust of air to and from the cylinder 138 will later be described.

The piston 122, because of the inertia of the massive cylindrical ram 74 as the ram rises, must be cushioned to prevent its striking a hard blow against the cylinder head 146. To this end a bumper cylinder 150 (Fig. 9) extends up from the head 146 of the main cylinder 138 and has a head 152 secured upon its upper end. A bumper piston 154, having a depending stem 156, is movable up and down in the bumper cylinder 150, the stem being guided by a bronze bearing bushing 158 and a bronze packing gland 160 between which are held fibre packing rings 162. The space between the piston 154 and the wall of the bumper cylinder 150 is sealed by a leather packing cup 146 held against the upper face of the piston by a clamping disc 166 and screw 168.

An air pressure conduit 170 connected to a conduit 196 (shown in Figs. 6 and 11 and later to be described) communicates, through a conduit 172, with the space below the bumper piston 154 and also, through a needle valve 174 and conduit 176, with the space above the bumper piston. With the air pressure turned off and the ram 74 down, the pressures above and below the bumper piston 154 will be equal and the bumper piston will rest upon the gland 160, with the stem 156 extending down into the main cylinder 138. When the air pressure is turned on and the ram 74 rises, it will strike the depending stem 156 and compress the air above the bumper piston 154. The needle valve 174 impedes the escape of air above the bumper piston 154 and thus causes the pressure above the bumper piston to build up and cushion the upward stroke of the piston rod 74. The extent of such cushioning is determined by the adjustment of the needle valve 174. Upon descent of ram 74, piston 154 will resume its original down position because the pressure coming from conduit 170 is the same on the top and bottom of piston 154 but due to the larger effective area of the top of the piston 154, the downward force will exceed the upward force and as stated piston 154 will move to down position.

A valve system for controlling the admission and exhaust of air to and from the main cylinder 138 comprises a pair of cylindrical valve casings 178 and 180 (Fig. 11 and Figs. 12 to 15 incl.) mounted on the top cross member 78 and having their axes vertical. The valve casing 178 has three ports numbered 182, 184 and 186 respectively and it houses a rotary valve 188 having three intercommunicating openings 190, 192 and 194. The port 182 communicates with the duct 144 (see also Fig. 9) leading to and from the main cylinder 138; the port 184 is an inlet port and it communicates with the conduit 196 (see also Fig. 6) leading from the reducing valve 64; and the port 186 communicates through a duct 198, with a port 200 in the valve casing 180. Another port 202 in the valve casing 180 communicates, through a duct 204, with the air pressure conduit 196; and a third port 206 in the valve casing 180 communicates with the atmosphere through a duct 208 and thus serves as an exhaust port. Housed within the valve casing 180 is a rotary valve 210 having three intercommunicating openings 212, 214 and 216.

The valve 210 is operated by a treadle 218 (Figs. 1 and 2) fulcrumed on a bracket 220 fixed on the base 30, the treadle being normally held up to a stopped position by a spring 222. A rod 226 is pivotally connected at its lower end to the treadle 218 and at its upper end to a lever 224. The lever 224 is fulcrumed on the base 30,

and is connected to the lower end of a wire 228 which constitutes the operative element of a Bowden cable having a sheath 230 surrounding the wire and enabling it to transmit a push as well as a pull. The sheath 230 is secured to the outside of the base 30 and to one of the uprights 82 of the upper frame. The upper end of the wire 228 (Fig. 10) is attached to a rocker arm 232 (see also Fig. 11) extending from an upright shaft 234 which has its lower and upper end portions engaged in bearings in one of the uprights 82. The upper end of the shaft 234 is secured to the valve 210 and the arrangement is such that depression of the treadle 218 will transmit a pull through the wire 228 and thereby rock the shaft 234 and the valve 210 counterclockwise through an angle of ninety degrees. Likewise release of the treadle 218 enables the spring 222 to turn the valve 210 clockwise through an angle of ninety degrees.

The valve 188 is operated automatically by a pair of upper and lower spiral cams 236 and 238, respectively, secured on an upright shaft 240 (Figs. 1, 2, 10 and 11) which has bearings in the upper frame. A pin 242 (Fig. 2) on one of the ram extensions 118 engages the upper cam 236 as the ram 74 rises and thereby turns the shaft 240 counterclockwise through an angle of sixty degrees. This same pin 242, as the ram 74 descends, engages the lower cam 238 and thereby turns the shaft 240 clockwise through an angle of sixty degrees. The cam shaft 240 is geared to the valve 188 by sprocket wheels 244 (Fig. 11) and 246 and a chain 248, the gear ratio being such that a sixty degree rotation of the cam shaft causes a ninety degree rotation of the valve. An idler pulley 250 is provided for adjusting the tension of the chain 248.

From the foregoing description it will be seen that there has been provided a power hammer having adjustable features which make it possible for the dies to be set in correct alignment at a great saving of time. The dies 20 and 22 may first be adjusted forwardly or backwardly in the usual manner by the release and re-securing of gibs 28 and 76. If the dies at this point are not aligned laterally, the adjusting screws 86 may be brought into use to shift the entire upper frame including the ram 74 and associated guide rods 116 either to the right or to the left as may be needed to align the dies in this direction. If it appears that the misalignment is caused by angular disparity, this may be corrected through the operation of the anvil adjusting screws 36. Upon bringing the dies into correct angular relationship, if it is found that there is still any longitudinal or transverse misalignment, the final correction may be made through the use of the transverse adjusting screws 86 or through the release of either upper or lower gib 76 or 28 and the shifting of the appropriate die toward the front or the rear of the machine.

The operation of the illustrated power hammer will now be described. Assuming the hammer to be idle and the air pressure to be turned off, the ram 74 will be down, with the upper die 22 resting upon the lower die 20 and with the valves 188 and 210 occupying the positions shown in Fig. 12. When the air pressure is turned on, air will pass from the conduit 196 through the valve 188 and the duct 144 and raise the ram 74. As the ram rises it will cause the upper cam 236 to turn the valve 188 to the position shown in Fig. 13 and, although when the valve 188 is in this position it blocks the inlet port 184, nevertheless air can pass through the duct 204, port 202, valve 210, port 200, duct 198, port 186, valve 188, port 182, duct 144 and so into the cylinder 138 and thereby maintain the ram 74 at the upper end of its stroke. Upon depression of the treadle 218, the valve 210 will turn counterclockwise from the position shown in Figs. 12 and 13 to the position shown in Fig. 14 and thereby block the admission of air through the port 202 while, at the same time, it will connect the duct 198 with the exhaust duct 208, permitting air to escape to the atmosphere from the cylinder 138. The heavy ram 74 will thereupon drop of its own weight and the weight of its associated parts and the

upper die 22 will strike the work piece and thereby in cooperation with the lower die 20 form the work piece to a desired shape. A complete lowering of the treadle will permit air to escape rapidly from the cylinder and thus enable the ram 74 to deliver a heavy blow; a partial depression results in a lighter blow. The pin 242, as the ram 74 completes its downward stroke, engages the lower spiral cam 238 and thereby causes the valve 188 to turn clockwise through an angle of ninety degrees to the position shown in Fig. 15, which is the same as the position shown in Fig. 12.

If the operator continues to hold the treadle 218 down, the valve 210 will remain in the position shown in Figs. 14 and 15 and air will enter the cylinder 138 through the valve 188 while at the same time the escape of air from the conduit 196 will be blocked by the valve 188 and the escape of air from the duct 204 will be blocked by the valve 210. The ram 74 will thereupon rise and, as it completes the upper portion of its stroke, it will cause the valve 188 to turn counterclockwise from the position shown in Fig. 15 to the position shown in Fig. 14. With both valves in the positions shown in Fig. 14, air from the cylinder 138 will escape through the exhaust duct 208 and the ram 74 will descend and this cycle will be repeated as long as the treadle 218 is held down.

When, however, the operator releases the treadle 218, the valve 210 will turn clockwise through ninety degrees to the position shown in Figs. 12 and 13, blocking the escape of air from the conduit 196 and the duct 204. Now, if the ram 74 is down, the valve 188 will occupy the position shown in Fig. 12 and will admit air to the cylinder 138. The ram 74 will thus be raised and the valve 188 will turn to the position shown in Fig. 13 and the hammer will remain at rest in raised position until the next depression of the treadle 218. If, on the other hand, the ram 74 is up when the treadle is released, the valves 188 and 210 will remain in the positions shown in Fig. 13 until the treadle is depressed. Thus, by releasing the treadle 218 as the ram completes its first downward stroke, the operator can prevent the ram 74 from delivering another downward stroke until he again depresses the treadle; or, if he continues to hold the treadle down, he can cause the piston rod to make as many downward strokes as he pleases.

In connection with the operation of the hammer as has just been explained, the significance and function of the four air cylinders 44 that support the hammer should be explained in more detail.

In conventional hammers of the type known to the art, it has been customary in many instances to support the hammer on springs but the supporting strength of the springs is not subject to adjustment. On the other hand, the air pressure that may be fed to the supporting cylinders 44 of the present construction may be varied at will by changing the setting of valve 64 or in case it was found not desirable to vary the pressure in pipe 196 then an additional valve like valve 64 could be introduced in the line 62, thereby to provide for exact control of the pressure in the four air cylinders 44.

In the operation of a power hammer of the present type it is customary and desirable to vary the force of the blow provided by the hammer according to the type of work being produced. As the blow is varied the compression and reaction of the supporting elements will vary according to the force of the blow. When springs are used as the supporting elements it is necessary that the springs be strong enough to absorb the heaviest blows and under such circumstances the spring, after being compressed in absorbing the blow will cause an upward movement of the entire hammer to an elevation above the normal position of rest. The machine will then descend again compressing the spring and continue to bounce up and down in an oscillating manner until the vibration has completely damped itself out. This is objectionable and accordingly, in prior art devices snubbers of one type or

another have been introduced in an attempt to minimize the vertical vibration set up by the springs.

If a lighter hammer blow is needed for the work in question there is no means of varying the compressibility of the springs and as a result the most that can be hoped for through the use of springs is an average result in the absorption of blows of different force.

On the other hand, through the use of air cushions of the type disclosed herein in which the air pressure therein may be varied it will be seen that when heavy blows are to be made with the hammer the air cylinders may be filled with an air pressure greater than that needed to merely lift the machine to its normal working position. The heavy blow will be sufficient to compress the air in the cylinders, thereby to absorb the blow and on the rebound the piston 40 will engage the rubber buffer 68 which quickly and effectively damps the vertical oscillation.

If the blows to be applied by the hammer are lighter, then the air pressure in the cylinders may be reduced until in the situation of the lightest blows by the hammer there will merely be enough air pressure in the cylinders to have moved the four pistons to the tops of their strokes. That is to say, the pressure in the cylinders 44 will just be sufficient to hold the pistons 40 against buffers 68. The light blows are then effectively absorbed as the four pistons 40 move downwardly against the lower pressure air and again, the rebound and tendency to oscillate is absorbed by the buffers.

From the foregoing it will be understood that the utilization of air cylinders achieves results not obtainable through the use of springs, namely, the supporting force can be varied to a pressure best calculated to absorb the particular hammer blows and secondly, means for snubbing the rebound can simply and easily be introduced in the cylinders on the upper sides of the pistons.

Obviously, the air cushions of the present type may be used with any type of hammer whether of fixed or variable blow. If of the fixed type, the pressure in the cylinders will be set at a fixed pressure which provides the greatest shock absorbing qualities. If the hammer is of the type in which the blow may be varied, of which the present construction is one, then means will be provided for varying the pressure in the cylinders as the striking force of the hammer for particular types of work is varied.

Through the use of the air cushion supports it is possible to use a lighter anvil than would be the case if the hammer were mounted directly on the floor. While this is also true of hammers mounted on springs still in the latter case it does not permit of the use of as light an anvil as in the case of the air cylinders because of the inability to vary the supporting spring force.

It is my intention to cover all changes and modifications of the example of the invention herein chosen for purposes of the disclosure which do not constitute departures from the spirit and scope of the invention.

I claim:

1. In a power hammer, a base, an anvil carried by said base and rotatable only about a vertical axis, means associated with said base for adjustably rotating said anvil, a ram operating in an air cylinder, a frame carrying said air cylinder, said frame comprising a pair of uprights integrally joined by top and bottom cross members, said frame mounted on said base, said bottom cross member formed to define a vertical opening therethrough, the upper end of said anvil positioned in said opening and spaced on opposite sides from the walls of said opening, and means for shifting said frame transversely of said base for adjusting said frame with respect to said anvil whereby said ram may be adjusted transversely with respect to said anvil and said anvil may be adjusted angularly with respect to said ram.

2. In a power hammer, the structure set forth in claim 1, said ram having transverse extensions on its lower end, and two parallel guide rods attached to the top and bottom cross members and positioned between the said up-

rights, said extensions slidably engaging said guide rods.

3. In a power hammer, an upper die, a lower die, means for guiding the upper die for height-wise movement whereby the upper die operates to shape a work piece on the lower die, an anvil for supporting the lower die, a base having an upwardly facing annular surface, said anvil having a downwardly facing annular surface for cooperative engagement with the said annular surface of the base, said anvil having a depending stem, said base having a bearing for the cylindrical surface of said stem in which bearing the anvil can be rotated about a vertical axis only, and a pair of adjusting screws threaded in said base and having ends engaging recessed portions of the anvil whereby the screws can turn the anvil in opposite directions respectively, thereby effecting rotary adjustment of the lower die with respect to the upper die.

4. In a power hammer, the structure set forth in claim 3, said means for guiding the upper die for heightwise movement comprising a rigid upper frame formed of a pair of uprights rigidly joined by top and bottom cross members and including two spaced parallel guide rods between said uprights, a cylindrical ram mounted in a bearing in the upper cross member of said frame, said ram having oppositely disposed extensions on the lower end thereof in surrounding and sliding engagement with said guide rods.

5. In a power hammer, a base, an anvil carried by said base, an upper frame having spaced uprights connected by top and bottom cross members, a blow applying element comprising a massive cylindrical ram longer than its diameter carried by said upper frame in a bearing for vertical movement, said ram constituting the major portion of the weight of said element, dies carried by said anvil and ram between which a work piece may be formed upon the descent of said ram, a transverse extension at the lower end of said ram, two guiding means integral with said upper frame and located between said uprights and on opposite sides of said ram for cooperation with said extension whereby said ram will be supported against deflection at three triangularly disposed bearings, a cylinder above said frame, said ram movable in said cylinder and having a diameter greater than one-half the diameter of said cylinder, and a piston attached to the upper end of said ram and slidably in said cylinder whereby said ram may be raised and dropped by the application of fluid pressure, said anvil being rotatable about a vertical axis for a limited angular movement, said frame being adjustable transversely of said anvil, and said dies being adjustable with respect to said ram and anvil in a direction at right angles to the direction of said frame adjustment.

6. In a power hammer, an upper frame for supporting a ram and upper die, said frame comprising a pair of uprights integrally joined by top and bottom cross members, a vertical opening through said bottom cross member, an anvil adjustable about its vertical axis for supporting a lower die, a base for supporting said anvil and said upper frame, a pair of members extending up from the base and rigid therewith, and a pair of horizontally extending oppositely directed adjusting screws threaded through said upwardly extending members and having their ends engaging portions of the bottom cross member of said upper frame whereby the screws can move the upper frame in opposite directions respectively, thereby to adjust the said upper die transversely with respect to the said lower die, said anvil having an annular horizontal under surface resting on a cooperating annular surface of said base and having an upper extension positioned

within the confines of the said vertical opening through said bottom cross member but spaced on opposite sides therefrom.

7. Means for resiliently supporting a power hammer of the type having a base on which are mounted the operating instrumentalities of the hammer, said instrumentalities including a ram, said means comprising a supporting and shock absorbing system comprising a plurality of upright piston rods supporting said base and all associated operating instrumentalities, a piston on each rod, a cylinder in which each piston can reciprocate, said cylinders being adapted to rest upon a floor, a conduit for conducting a gas under pressure to each cylinder below each piston, and a check valve in said conduit for preventing a sudden back flow of pressure gas upon impact resulting from descent of said ram, thereby enabling the pressure gas to cushion the impact and thus minimize the shock transmitted to the floor.

8. Means for resiliently supporting a power hammer as set forth in claim 7 and a pressure regulating valve in said conduit whereby the pressure in each of the said cylinders may be varied to provide optimum resilient support of said hammer according to the force of the blow currently being applied to the work by said ram.

9. In a power hammer, a base, an anvil supported by said base for receiving a blow from a falling hammer, an upper frame, a hammer mounted for reciprocation in said upper frame, means for actuating said hammer including means for controlling the velocity of said hammer at the moment of impact with said anvil, vertically compressible supporting means for said base, said supporting means comprising air cylinders and pistons movable therein, means for supplying compressed air to said cylinders to move said pistons and thereby raise said base and means for varying the said air pressure in said cylinders thereby to produce optimum shock absorbing conditions as required with respect to hammer blows on said anvil of particular force.

10. In a power hammer as set forth in claim 9 each cylinder including therein a buffer element located to be engaged by said piston upon the upward rebound of said piston following the absorption of the force of a hammer blow by further compression of the air in said cylinders.
